UNITED STATES PATENT OFFICE.

LARS JOHNSON, OF IRON MOUNTAIN, MICHIGAN.

SNOWPLOW.

Application filed September 28, 1921. Serial No. 503,826.

To all whom it may concern:

Be it known that I, LARS JOHNSON, a citizen of the United States, residing at Iron Mountain, in the county of Dickinson and State of Michigan, have invented certain new and useful Improvements in Snowplows, of which the following is a specification.

This invention relates to railroad track plows and more particularly to a novel and improved snow plow or track cleaner.

The primary object of the invention is to produce a snow plow wherein the mold boards are provided with track engaging rollers or guides disposed on opposite sides of the supporting wheels, for properly maintaining the plow in its operative position on the track.

A still further object of the invention is the construction of a snow plow of the class above set forth, wherein the plows are provided with double operating means for raising and lowering the same to their inoperative positions, including further provision for independently disengaging the guide wheels from the tracks as when passing over switches.

Another and very important object of the invention is the provision of a snow plow designed for use for cleaning and clearing heavy snow drifts from a railroad road bed, and one in which the parts are extremely simple in construction, easily assembled, rigid and durable, highly efficient in operation, practical and capable of being manufactured at a very low cost whereby its commercial possibilities are greatly enhanced.

The invention will be best understood from a consideration of the following detailed description taken in connection with the accompanying drawing forming a part of this specification, with the understanding, however, that the invention is not confined to any strict conformity with the showing in the drawing, but may be changed and modified so long as such changes and modifications mark no material departure from the salient features of the invention as expressed in the appended claims.

I attain these objects in the accompanying drawings, wherein:

Figure 1 is a side view of the plow looking from the left.

Figure 2 is a plan.

Figure 3 is a longitudinal section showing the operating mechanism of the plows and the guides.

Figure 4 is a detail view of the guide lifting mechanism; and

Figure 5 is a sectional view taken on the line 5—5 of Fig. 2.

Referring now to the drawings wherein like reference characters designate corresponding parts throughout the several views, the frame or body of the plow comprises a longitudinal, heavy beam 5, side and end connecting beams 6, 7, which constitute the triangular frame supporting structure for the plow shares, subsequently to be referred to, a single front, flanged wheel 8, rotatable on its shaft 9, and the rear flanged wheels 10 and 11 and their axle 12 journaled in suitable bearings 13 are adapted to support the frame and the plow on the tracks 15 in the manner well understood.

The said frame is also provided with transverse brace bars 16, 17, 18, connecting the beams 5 and 6 of the frame which provides for a support for the operating mechanism, subsequently to be referred to, as well as bracing the frame proper in producing a very rigid structure.

Mounted in suitable bearings 19 and 20, on the beam 6, I have provided a rock shaft 21, which cooperates with a short rock shaft 22, mounted in suitable bearings 23 and 24, on the side beam 5. Suitably connected to the respective rock shafts I have provided a plurality of slightly curved standards 25, to which the mold board 26 is connected, as well as the mold board 27, on the opposite side thereof, the respective mold boards meeting at their forward ends and being curved as shown as at 28 for properly digging into a snow drift and deflecting the same to both sides of the track. The respective standards 25 are connected to the braces 16, 17, by diagonal braces 29, 30, a U-shaped plate 31 being provided at the upper end of the said braces 29, 30, to permit of the vertical movement of the plow shares when the same are to be raised to their inoperative position from the track.

A transverse top cross bar 32 connects certain of the standards of the respective mold boards 26, 27, as clearly shown by Fig. 2 of the drawings.

Referring now particularly to Figures 2

and 3, it will be observed that each rock shaft 21, 22 is provided with an angularly extending lug 32 connected by links 33 to a lever 34, said lever being pivoted intermediate 5 at its ends at 35 to a supporting post 36 and connected at its opposite end by links 37 to an actuating lever 38, disposed rearwardly of the frame and pivoted as at 39 to a short post 40 mounted on the cross beam 10 17. By reason of this construction, it will be readily seen that upon actuating the lever 38 the same will rock the shafts 21 and 22, which are connected by means of radially extending arms 21' with the standards 25 15 and consequently raise the plows sufficiently to clear the track and be moved to their inoperative positions. In actual practice, however, it is desired to accomplish the same purpose through the intermediary of a longitudinally extending rod 41, operable by compressed steam from the engine, said rod 41 being connected by a link 42 to a belt crank lever 43, said belt crank lever being connected in turn by a link 44 to the lever 34, 20 25 at a point adjacent its rear end, as clearly disclosed by Fig. 3 of the drawing.

It will thus be seen that I have provided both a mechanical and a manually operable mechanism for raising the mold board so 30 that should the mechanical means be disconnected the manually operable mechanism may be resorted to for actuating the levers to dispose the respective plows for the purpose intended.

35 In order to properly maintain the plows in their working position and offset the inward strain on the mold boards when engaging heavy snow drifts, I have provided guide rollers on each side of the frame, one 40 adjacent the front supporting wheel 8 and the other adjacent the diagonally opposite wheel 10. The front guide roller 45 is connected by an arm 46, pivotally connected to one of the standards, the said roller being 45 grooved, as shown at 47 to engage the top flange of the rail and on the opposite side of the flange 48 of the front supporting wheel. A lifting arm 49, pivotally connected to a lever 50, operable over a tooth 50 rack 51, is further provided with the usual 55 spring pressed pawl 52 and actuating rod 53, whereby the guide roller may be moved to its operative and inoperative position from a point adjacent the operating lever 55 38, which raises the plows above referred to. The guide roller 46^a disposed adjacent the wheel 10 is similarly constructed, but in this instance it will be observed that the tooth rack 54, mounted between the rear bar 7 and 60 the brace bar 16 is at right angles to the mold board 26, so that the actuating rods 55 of the lever 56 and spring pressed pawl 57 may be actuated from a position adjacent the ends of the actuating rod 53 and 65 the lever 38, above referred to. In each

instance the actuating rods are supported by suitable guides 57, 58, as clearly shown by Fig. 3 of the drawing.

A balancing weight 58' is positioned on the guide beam 5 and preferably at the rear end thereof to offset the weight of the mold board 26, which as shown extends throughout the entire length and on one side of the frame, and as the usual coupling 59, preferably connected intermediate 70 the rear beam 7 provides for the ready attaching of the snow plow to the front of an engine, whereby the same may be moved over the track bed to perform the work intended. 75 80

In the accompanying drawings, I have illustrated my invention embodied in one form by way of example, and which in practice has been found to be highly satisfactory in obtaining the desired results. It will be 85 obvious, however, that other embodiments may be adopted, and that various changes in the details of construction may be resorted to by those skilled in the art without departing from the spirit and scope of the 90 invention. It is furthermore understood that the invention is not necessarily limited or restricted to the precise elements shown except in so far as such limitations are specified in the subject matter being claimed. 95

Having thus described my invention what I claim as new and desire to secure by Letters Patent of the United States is:—

1. In a snow plow, the combination with a triangular frame, supporting wheels carried by the frame disposed in a vertical plane for engaging railroad rails, slideable mold boards carried by the frame, and angularly disposed wheels carried by the frame for engaging the sides of the railroad rails. 100 105

2. In a snow plow, the combination with a car body, curved standards and mold boards carried by the body and mounted on each side thereof, rock shafts journaled in bearings on the sides of the frame, lugs extending inwardly from each of the rock shafts, a pivoted lever and links connecting said lever to said lugs, and means for actuating said lever and rock shafts to raise and lower said mold boards with respect to the body. 110 115

3. In a snow plow, the combination with a car body, a pair of standards and mold boards carried by the body and mounted on each side thereof, rock shafts connected to the standards of the respective mold boards, means for actuating said rock shafts to raise and lower the mold boards, track engaging rollers attached to each mold board and disposed below the body and means for independently raising and lowering said rollers operable from a position at the rear end of said body. 120 125

4. In a snow plow, the combination of a car body, curved standards and mold boards 130

carried by the body on each side thereof, rock shafts connected to the standards of the respective mold boards, means for manually actuating said rock shafts to raise 5 and lower the mold boards, track engaging rollers on each side of the body, a supporting arm for each of said rollers pivotally attached to the inner sides of the mold boards, and manually operable means for drawing

either of said rollers into inoperative position when the mold boards are raised and lowered.

In testimony whereof I affix my signature in presence of two witnesses.

LARS JOHNSON.
